UNITED STATES PATENT OFFICE.

JOSEPH B. STRAUSS, OF CHICAGO, ILLINOIS.

LIFT BRIDGE.

Application filed October 29, 1923. Serial No. 671,321.

This invention relates to lift bridges and has for its object to provide a new and improved device of this description. It has as a further object to provide a lift bridge which can be raised bodily to any desired height without the use of cables. The invention has as a further object to provide a lift bridge which shall have a low cost of construction and maintenance, and at the same time have greater efficiency and safety. The invention has further objects which are more particularly pointed out in the following description.

Referring now to the drawings—

Figure 1 is a side elevation showing one form of device embodying the invention.

Figure 2 is an end elevation of the device shown in Figure 1, showing the bridge closed.

Figure 3 is a view similar to Figure 2, showing the bridge in full lines partially opened, and in dotted lines completely opened.

Figure 4 is an enlarged view showing the wedge between the bridge span and the pier.

Like numerals refer to like parts throughout the several figures.

Referring now to the drawings, the main span 1 of the bridge may be constructed in any desired manner. This main span is rotatably connected at each end to the rotatable supports 2. In the construction shown this connection is made by the pivots 3. The rotatable supports 2 are rotatably connected to fixed supports 4. This connection is made by means of the pivots 5. It will be noted that the rotatable supports 2 are vertically disposed when the bridge is closed, and rotate in a plane substantially at right angles to the axis of the main span. The main span is counterweighted in any suitable manner, as for example, by providing counterweights 6 which are connected to the rotatable supports 2. Some means is provided for moving the rotatable supports 2 about their pivotal connections so as to move the bridge laterally and also lift and lower it.

In the construction shown the main span 50 is provided with the operating house 7 which may be located at any suitable point. This house contains the motor 8 which drives the shafts 9 and 9^a. Connected with these shafts are the gears 10 and 10^a. The shafts 9 and 9^a preferably pass through the

axes of the pivotal connection of the main span with the rotatable supports 2. The gears 10 and 10^a engage gears 11 and 11^a connected with shafts 12 and 12^a which shafts are provided with gears 13, 13^a. 60 These latter gears engage gears 14, 14^a on shafts 15, 15^a which are provided with gears 16, 16^a which mesh with the curved racks 17, 17^a on the fixed supports 4. The gears 10 to 16, and 10^a to 16^a and associated parts 65 are connected with the rotatable supports 2. The rack 4 is preferably a circular rack so that the bridge may be turned a complete circle if desired. Some means is provided when the main span is in its closed position 70 to relieve the pivots from the load. In the construction shown this is accomplished by the live load wedges 18. These wedges may be operated in any desired manner. As herein shown there are two of them, one 75 at each end of the bridge. These wedges are operated by motors 19 through the train of gearing 20 and 21. The gears 21 are provided with arms 22, which move the wedges 80 into and out of place.

When it is desired to open the bridge the shafts 9 and 9^a are rotated and this rotates through the intermediate mechanism, the gears 16 and 16^a, which causes said gears 85 to move along the rack 17 and 17^a, and rotate the rotatable supports 2 about their pivots 5. This moves the main span outwardly and upwardly, the counterweights 6 counterbalancing the main span in all of its various positions. When the rotatable supports 2 have moved through an arc of 180°, the main span will be in its full open position as shown in dotted lines of Figure 1. It will be noted that in all of its various positions, the main span is maintained right 90 side up. In the construction shown the floor of the main span is at or near the lower end thereof, and this floor is held in this relative position and in a horizontal position during all the various positions of the main span. It will be noted that when the main span is in its maximum up or lifted position, the counterweights 6 extend across the roadway, thereby closing the roadway so as to prevent vehicles and the like from running into the channel. 100

When it is desired to lower the main span, the movement may be continued so as to make a complete circle and bring the main span back to its closed position or the main 105 110

span may be brought back to its closed position by reversing the movement.

I claim:

- 5 1. A swinging lift bridge comprising a main span, rotatable supports at each end thereof to which said main span is pivotally connected, fixed supports on which said rotatable supports are rotatably mounted, counter weights connected with said rotatable supports to counterbalance the weight of the main span, the rotatable supports being at right angles to the longitudinal axis of the main span.
- 15 2. A swinging lift bridge comprising a main span, rotatable supports at each end thereof to which said main span is pivotally connected, fixed supports on which said rotatable supports are rotatably mounted, counter weights connected with said rotatable supports to counterbalance the weight of the main span, the rotatable supports being at right angles to the longitudinal axis of the main span and means carried by the main span for rotating the rotatable supports to open and close said main span.
- 30 3. A swinging lift bridge comprising a main span, two rotatable supports, one at each end of said main span, stationary supports on which said rotatable supports are rotatably mounted, said rotatable supports connected at one end to the main span substantially on its center line, counter weights connected with the other ends of said rotatable supports, said rotatable supports being at right angles to the longitudinal axis of the bridge.
- 35 4. A swinging lift bridge comprising a main span, two rotatable supports, one at each end of said main span, stationary supports on which said rotatable supports are rotatably mounted, said rotatable supports connected at one end to the main span substantially on its center line, counter weights connected with the other ends of said rotatable supports, the stationary supports and rotatable supports being in substantially parallel planes, a motor mounted on the main span, shafts connected with said motor and extending to said movable supports, shafts mounted on said movable supports rotatably connected with the shafts on the

main span, racks on the stationary supports with which the shafts on the rotatable supports are operatively connected.

5. A swinging lift bridge comprising a main span, two rotatable supports, one at each end of said main span, stationary supports on which said rotatable supports are rotatably mounted, said rotatable supports connected at one end to the main span substantially on its center line, counter weights connected with the other ends of said rotatable supports, the stationary supports and rotatable supports being in substantially parallel planes, a motor mounted on the main span, shafts connected with said motor and extending to said movable supports, shafts mounted on said movable supports rotatably connected with the shafts on the main span, racks on the stationary supports with which the shafts on the rotatable supports are operatively connected, the shafts on the main span extending through the axes of the pivotal connections between the main span and the rotatable supports.

6. A swinging lift bridge comprising a main span, rotatable supports with which said main span is rotatably connected, fixed supports upon which said rotatable supports are rotatably mounted, operating mechanism for moving the rotatable supports to open and close the main span, and means for preventing oscillation of the main span while it is being moved.

7. A swinging lift bridge comprising a main span, fixed supports at the opposite ends of said main span, rotatable supports at right angles to the longitudinal axis of the main span and rotatably connected with said fixed supports and to which the main span is rotatably connected, operating mechanism for rotating said rotatable supports to open and close the main span and means mounted on the main span for relieving the pivotal connections between the main span and the fixed supports from the weight of the main span when it is closed.

Signed at Chicago county of Cook and State of Illinois, this 20th day of October 1923.

JOSEPH B. STRAUSS.
